UNITED STATES PATENT OFFICE.

HERMAN J. ENGBRECHT, OF CHICAGO, ILLINOIS. ASSIGNOR TO STANDARD OIL COMPANY, OF WHITING, INDIANA, A CORPORATION OF INDIANA.

SUCTION-OPERATED LIQUID-DISPLACING APPARATUS.

Application filed May 11, 1925. Serial No. 29,477.

My invention relates to apparatus wherein liquid is caused to be moved from one location to another by the exertion of suction in the receptacle to which the liquid is to be supplied; and, more particularly, though not exclusively, to such a type of apparatus provided for evacuating the oil casings of automobiles and, more especially, the crank cases thereof, where change of oil therein is desired; and particularly where the suction, for effecting the discharge of the liquid into the receiver of the apparatus, is produced by compressed air passing through an ejector the suction inlet of which communicates with the receiver for the liquid.

My primary objects are to provide in connection with the exhaust for the suction-producing fluid employed in an apparatus of the character stated, means whereby the noise which would be produced if the fluid exhausted directly to the atmosphere, shall be muffled; and to provide for the utilization of the exhausting fluid-pressure as the means of operating a movable, preferably rotatable, member preferably bearing any suitable advertising matter.

As I have devised my improvements for use more particularly in a crank-case-evacuating apparatus such as that disclosed in my pending application for U. S. Letters Patent Serial No. 13,819 filed March 7, 1925, I have chosen to illustrate it in such an apparatus, but not, however, with the intention of limiting its use to such an apparatus.

Referring to the accompanying drawings:—

Figure 1 is a view in vertical sectional elevation of a portion of an apparatus like that disclosed in my said application, and to which my present improvements are applied, a portion of the upper part of the apparatus being broken away. Fig. 2 is an enlarged view in elevation, partly sectional, of a device embodying my improvements showing the manner of mounting my device upon the suction-producing fluid-pressure exhaust-pipe of the evacuating apparatus to which it is applied. Fig. 3 is a view in sectional elevation of the top portion of the receptacle into which the oil is drawn, showing the ejector device mounted therein for producing suction in the receptacle; and Fig. 4, a section taken at the line 4—4 on Fig. 2 and viewed in the direction of the arrows.

In explanation of the illustrated apparatus

as to those features forming the subject of my said pending application, it may be stated that 10 represents a receptacle for receiving the oil, this receptacle being provided in its top with an ejector-device 11 supplied with compressed air from any suitable source, through a pipe 12, the suction-inlet of the ejector being represented at 13 and opening into the upper portion of the receptacle 10, it being understood that compressed air discharging upwardly from the pipe 12 through the ejector device 11 and out through a pipe 14, creates suction, through the opening 13, in the receptacle 10. The pipe 12 is loosely surrounded by a pipe 15 which opens at its upper end into the upper part of the receptacle 10 and at its lower end connects, by a passage 16 in the bottom of the receptacle 10, with a pipe 17 which leads to a flexible hose-line (not shown), preferably equipped with a fitting, as set forth in said application, to facilitate its connection with the lower drain openings of crank-cases to be evacuated, and to which the suction created in the receptacle 10 is applied through the pipe 15, passage 16, pipe 17 and hose line referred to, to transfer the oil in the crank-case to the receptacle 10. The air pipe 12 is shown as leading outwardly from the standard 18 supporting the receptacle 10, this being in accordance with said application wherein the pipe 12 is connected with a valve (not shown) and located exterior of the standard 18, for controlling the supplying of air to the pipe 12, the valve connecting at its inlet with a pipe 12^a which would lead from the source of compressed-air for supplying the pipe 12.

In accordance with my present invention, I provide a motor positioned to be operated by the fluid-pressure exhausting from the pipe 14 and serving not only to muffle the exhausting pressure, but also to operate an advertising-bearing member carried by the rotor of the motor whereby the member is rotated, to attract attention, when the ejector device 11 is operating.

The construction of motor shown comprises a pair of diametrically disposed pipes 19 carried by, and extending relatively outwardly from, a cap 20 carried by the pipe 14, the inner ends of the pipes 19 communicating with the interior of the pipe 14. The outer ends of the pipes 19 are somewhat flattened vertically and slightly deflected, as

shown at 21 whereby the fluid pressure is suing therefrom issues in jets discharging somewhat tangentially. The rotor of the motor is represented at 22 and is shown as 5 in the form of a hollow sphere through an opening 23 in the bottom of which, provided with a bearing sleeve 24, the pipe 14 upwardly projects to a point slightly above the center of the rotor. The upper part of 10 the rotor 22 is provided with a socket-bearing 25 adapted to bear upon a point-bearing 26^a provided on the upper end of a rod 26 secured to, and projecting upwardly from, the cap 20, whereby the rotor is freely rotatable. The rotor is provided about its inner 15 surface with a circular series of vanes 27 positioned for impingement thereagainst of the fluid-pressure discharging from the pipes 19, to effect rotation of the rotor 22, 20 the fluid-pressure discharging from the rotor through a series of relatively small apertures 28 in the bottom portion thereof whereby the noise of the exhaust is muffled.

The sign-bearing member referred to is 25 represented at 29 and is shown in the form of a triangular plate secured at an apex thereof in an ornamental head 30 rigidly secured in an opening 31 in the top of the rotor 22 to rotate therewith and which head 30 is shown as containing the socket-bearing 25.

While I have illustrated and described a particular construction embodying my invention, I do not wish to be understood as intending to limit it thereto as the same may 35 be variously modified and altered without departing from the spirit of my invention.

What I claim as new, and desire to secure by Letters Patent, is:

1. In a liquid displacing apparatus, the 40 combination of a receptacle for receiving the liquid, means for producing flow of liquid to the receptacle and involving in its operation the exhausting of fluid under pressure, a fluid-pressure-driven motor associated with said receptacle and in communication with the exhausting fluid, and a display device actuated by said motor.

2. In a liquid displacing apparatus, the 45 combination of a receptacle for receiving the liquid, fluid-pressure ejector means for discharging the liquid into said receptacle and comprising an exhaust pipe extending upwardly from said receptacle, and a fluid-pressure-driven motor mounted on the upper end of said pipe and in communication therewith.

3. In a liquid displacing apparatus, the 50 combination of a receptacle for receiving the liquid, means for producing flow of liquid to the receptacle and involving in its

operation the exhausting of fluid under pressure, an exhaust pipe extending upwardly from said receptacle and through which said exhausting fluid discharges, and a fluid-pressure-driven motor mounted on 65 the upper end of said pipe and in communication therewith.

4. In a suction-operated liquid-displacing apparatus, the combination of a receptacle for receiving the liquid, means for producing suction in said receptacle, and comprising an exhaust pipe extending upwardly from said receptacle, and a fluid-pressure-driven motor mounted on the upper end of 70 said pipe and in communication therewith. 75

5. In a liquid displacing apparatus, the combination of a receptacle for receiving the liquid, means for producing flow of liquid to the receptacle and the exhausting of fluid under pressure, and a fluid-pressure-driven motor and a muffler device in communication with the exhausting fluid. 80

6. In a liquid displacing apparatus, the combination of a receptacle for receiving the liquid, fluid-pressure ejector means for discharging the liquid into said receptacle, and a fluid-pressure driven motor, and a muffler device in communication with the exhaust of said ejector means. 85

7. In a liquid displacing apparatus, the combination of a receptacle for receiving the liquid, means for producing flow of liquid to the receptacle and involving in its operation the exhausting of fluid under pressure, and a fluid-pressure-driven motor in communication with the exhausting fluid, the rotor of said motor having a member projecting therefrom and rotatable thereby. 90

8. In a liquid displacing apparatus, the combination of a receptacle for receiving the liquid, means for producing flow of liquid to the receptacle and involving in its operation the exhausting of fluid under pressure, and a fluid-pressure-driven motor in communication with the exhausting fluid, said motor comprising a hollow external rotor with muffling apertures therein. 100 105

9. In a liquid displacing apparatus, the combination of a receptacle for receiving the liquid, means for producing flow of liquid to the receptacle and involving in its operation the exhausting of fluid under pressure, an exhaust pipe extending upwardly from said receptacle and through which said exhaust fluid discharges, and a fluid-pressure-driven motor in communication with said exhaust pipe, and comprising a rotor revolvably mounted on said pipe and actuating a display device. 110 115
